AUTOMATIC POULTRY FEED DISPENSER

Louis Paparazzo, Waterbury, and Alexander A. Bernatz, West Cheshire, Conn.; said Paparazzo assignor to said Bernatz

Application October 31, 1950, Serial No. 193,136

2 Claims. (Cl. 119—52)

1

This invention relates to poultry feeders, and more particularly to a hanging, traveling hopper type of feed distributor for large flocks of chickens or other fowl.

One object of this invention is to provide a device of the above character which is well suited for dispensing either wet or dry types of poultry feed or mash.

Another object is to provide a device of the above nature having a single or duplex feed hopper which may be raised or lowered in accordance with the various sizes of troughs from which the poultry is fed.

Another object of this invention is to provide a device of the above nature, including easily operated means to agitate the feed in the hoppers so that it will be dispensed at a uniform rate.

Another object is to provide a device of the above nature wherein the operator may adjust the rate of flow of the feed from the hopper to the feeding troughs.

A further object is to provide a device of the above nature which will be simple in construction, inexpensive to manufacture, easy to install and manipulate, compact, and very efficient and durable in use.

With these and other objects in view, there has been illustrated on the accompanying drawing one form in which the invention may conveniently be embodied in practice.

In the drawing,

Fig. 1 represents a perspective view of the feeding device and its associated troughs with sections broken away for clearness.

Fig. 2 is a partial end view of the device, also with sections broken away.

Referring now to the drawings, in which like reference numerals denote corresponding parts throughout the several views, the numeral 10 indicates the front end wall of a duplex feed hopper H, the rear end wall being indicated by the numeral 11. A pair of rectangular side walls 12, 12 interconnect the respective vertical ends of the end walls 10 and 11. The front end wall 10 is provided with a pair of outwardly and downwardly inclined extension portions 13, 13; likewise, the rear end wall 11 is provided with a similar pair of inclined extension portions 14 (only one shown).

The extension portions 13 and 14 are interconnected by a pair of rectangular inclined bottom plates 15, said bottom plates together forming the bottom of the hopper 11. The plates 15 slope downwardly and outwardly from the center toward the sides of the hopper in opposite directions.

2

The lower and upper ends of the side walls 12 are preferably formed with inwardly-bent angular portions 16 and flanges 17, respectively.

Means are provided for the adjustable suspension of the hopper H from an overhead I-beam rail 18 running the length of the chicken house. To this end, the rail has disposed in each of its sides, two pairs of rollers 19, each pair of which is rotatably fixed to a pair of hanger members 20. Each of the hangers 20 is provided with an opening through which pass a pair of chains 21, interconnecting respective upper end corners of said hopper. The chains may be fixed to the corners of the hopper as by being secured in openings in four corner angle iron pieces 22 extending upwardly above the top of the hopper. One end of each of the chains 21 is provided with a hook 23 adapted to be adjustably inserted into any desired link of its respective chain in order to adjust the height of the hopper. Alternatively, instead of using chains, the ends of the hopper may be connected to their respective hangers by means of rods provided with turnbuckles (not shown) within the spirit and scope of the present invention. In such a case, the adjustment of the height of the hopper may be made merely by operating the turnbuckles.

In order to control the rate of flow of feed or mash from the hopper through the openings between the bottom ends of the side walls 12, and 30 the respective bottom plates 15, provision is made of a pair of shutter members 24, adapted to be adjustably positioned against the outer sides of said openings. Each shutter member 24 comprises an elongated flat section 25, an angle iron 26 fixed outside the lower end thereof, and an elongated yieldable gasket 27, preferably of rubber, seated along said angle iron and fixed thereto, and to said flat section, as by rivets 28 (or bolts, not shown).

Each shutter member 24 is further provided with an angle iron 29, fixed along the outside of the flat section 25 near the upper end thereof, to which is fixed, as by bolts, the arms of each of a pair of hinges 30. The other arms of the hinges 30 are attached to the side walls 12 so that the shutters are swingable downwardly against their respective feed openings.

In order to adjust the rate of flow of the feed from the hopper, there is provided for each shutter a control crank 31, one end of which is fixed against the inside of one end of the angle iron 29 at a slight angle with respect to the vertical axis of the shutter member 24. The other end of the crank is equipped with a handle 32 for controlling 55 the position of the shutter member. An angle

iron flange 33, in which is cut a plurality of T-shaped slot openings 34, is mounted against the front end wall of the hopper in a horizontal position and serves to lock the shutter control cranks 31, and the shutter members 34 selectively at a plurality of positions.

Automatic means are also provided to agitate the feed in the hoppers so that it will not pack and clog at the dispensing openings. To this end, there is provided a pair of aligned agitator rods 35, each journaled between the end walls of the hopper at positions just within the feed dispensing openings. Each of the rods has fixed to it a plurality of agitator vanes 36 spirally disposed along the sides thereof. One end of each of the rods extends through the front end wall 10 and is equipped with a sprocket 31. Interconnecting the sprockets 31 for imparting simultaneous rotational motion to the agitator rods 35 is a drive chain 38, and the end of one of the rods is further provided with a rotatable crank member 39 and a handle 40.

The hopper is further provided with a pair of aprons A, comprising elongated bottom portions 41 and upstanding end portions 42 and downwardly extending skirt portions 44. The end portions are swingably mounted against and between the respective front and rear end wall extensions 13 and 14, as by headed pins 43.

A removable central partition P is provided for use in case it is desired to dispense different types of feed to the feed troughs.

Operation

In operation, the hopper H containing the feed or mash F is first adjusted for feed dispensing by springing the shutter control cranks 31 into the particular slot openings 34 which serve to hold the shutter members 34 in the desired positions. Thereafter, it will merely be necessary for the operator to push the hopper along the rail 18 from one end of the chicken house to the other, meanwhile manually rotating the crank 39 to insure an even flow of feed from both sides of the device into the troughs T. The apron A may be folded upwardly to permit the device to be moved back to the original end of the chicken house without disturbing the chickens.

It should be noted that the feed-dispensing openings are independently adjustable so that different amounts, or even different types of feed or mash may be supplied to the separate troughs T.

It will be understood that the outer under edges of the aprons rest against the sides of their respective troughs and thus insure that the feed is properly directed into said troughs.

Adjustment to different heights of troughs for different sizes of poultry is readily made by raising or lowering the hopper by shortening or lengthening the suspension chains 21.

One advantage of the improved device resides in the rapidity and ease with which large flocks of poultry can be fed.

Another advantage is its ready adaptability to different sizes of poultry.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In an automatic poultry feeder, a feed-containing hopper having a pair of fixed vertical end walls, a fixed inclined bottom plate, a fixed vertical side wall having its lower edge spaced from said bottom plate leaving a longitudinal feed passage opening therebetween, a longitudinal shutter plate pivoted to said side wall, said shutter plate having a flexible strip secured to its lower edge and adapted to yield to permit the passage of feed from said hopper into a trough below it, a horizontal flange on one end of said hopper, said flange having a plurality of spaced apart open notches, and an inclined rod pivotally secured to said shutter and selectively insertable in any one of said notches to hold said shutter in any desired adjusted position.

2. In an automatic poultry feeder, a feed-containing hopper having a pair of fixed vertical end walls, a fixed inclined bottom plate, a fixed vertical side wall having its lower edge spaced from said bottom plate leaving a longitudinal feed passage opening therebetween, a longitudinal shutter plate pivoted to said side wall, a longitudinally extending apron pivotally secured to the lower portions of the end walls of said hopper to guide the feed from said hopper to a trough below it, said apron being foldable upwardly away from said trough when the desired quantity of feed has been dispensed at one location to permit the feeder to be moved longitudinally to a different location without disturbing poultry which may be feeding from said trough.

LOUIS PAPARAZZO.
